PERFORATING DEVICE

Daniel A. Brennan, Chicago, Ill.

Application May 29, 1937, Serial No. 145,417

15 Claims. (Cl. 164—91)

The invention relates to perforating devices and more particularly to portable devices adapted for perforating sheets of paper or the like to facilitate binding thereof with fasteners or the like in files or binders.

An object of the invention is to provide a simple and efficient perforating device embodying features to be described hereinafter to minimize frictional resistance between movable parts during the operation thereof.

Another object is to provide a perforating device with efficient, simple and inexpensive means to support vertical perforating elements or punches rigidly in position.

Another object is to provide a perforating device with novel means to positively withdraw the perforating elements after they have performed the punching operation.

Another object is to provide a perforating device with readily adjustable means to gauge the sheets to be punched and novel means to detachably retain said means in any predetermined position.

Another object is to provide a perforating device of the character referred to with novel means in the base thereof to clearly indicate the position of adjustment of the gauging means.

Another object is to provide a perforating device with novel means to support the base thereof.

Another object is to provide a sturdy and efficient perforating device embodying several practical improvements and especially a device the principle parts of which may be constructed of sheet metal economically.

The foregoing and such other objects of the invention, as will appear hereinafter as the description proceeds, will be more readily understood from a perusal of the following specification, reference being had to the accompanying drawings, in which:

Fig. 1 is a longitudinal vertical sectional view of one embodiment of the perforating device, showing parts in elevation.

Fig. 2 is a sectional view taken on line 2—2 of Fig. 1.

Fig. 3 is a plan view of the perforating device.

Fig. 4 is a perspective view of one of the punch guide standards.

Fig. 5 is a vertical sectional view taken on line 5—5 of Fig. 3.

Fig. 6 is a longitudinal vertical sectional view of a modified form of perforating device.

Fig. 7 is a fragmentary sectional view similar to Fig. 6, showing another modified construction.

Fig. 8 is a sectional view similar to Fig. 7, showing additional modifications.

Fig. 9 is a fragmentary longitudinal sectional view of another form of perforating device.

Fig. 10 is a rear elevational view of another

form of perforating device, showing portions partially broken away.

Fig. 11 is a vertical sectional view, taken on line 11—11 of Fig. 10.

Fig. 12 is a fragmentary sectional view of another modified construction showing parts in elevation.

Fig. 13 is a horizontal sectional view taken on line 13—13 of Fig. 12.

Fig. 14 is a fragmentary sectional view showing another modified form of construction.

Fig. 15 is a fragmentary vertical sectional view of one of the punch guide standards showing another modified form of construction.

Fig. 16 is a fragmentary sectional view, similar to Fig. 14, showing a modified form of construction.

Fig. 17 is a sectional view taken on line 17—17 of Fig. 16.

Fig. 18 is a fragmentary plan view of a perforating device embodying a modified form of gauge bar.

Fig. 19 is a sectional view taken on line 19—19 of Fig. 18.

Fig. 20 is a fragmentary plan view of the perforating device base shown with a modified form of gauge bar.

Fig. 21 is a fragmentary plan view of a portion of the perforator base showing another modified form of gauge bar, partially broken away.

Fig. 22 is a fragmentary plan view, similar to Fig. 18, showing another modified form of gauge bar.

Fig. 23 is a fragmentary plan view of a perforator base showing a gauge bar of modified construction.

Fig. 24 is a transverse vertical sectional view through a perforating device base, showing another form of gauge bar.

Fig. 25 is a sectional view, similar to Fig. 24, showing another form of gauge bar.

Fig. 26 is an elevational view of the gauge bar shown in Fig. 25.

Fig. 27 is a view, similar to Fig. 25, illustrating a gauge bar embodying other modified details.

Referring to the drawings, the perforating device illustrated in Figs. 1 to 5, inclusive, includes a base 11, which preferably is made of any suitable sheet material, such as steel, having its marginal edge portions bent downwardly to provide side walls 12 and end walls 13. The front end of the base may be rounded, as best shown in Fig. 3, with the end wall 13 thereof merging with side walls 12.

The base 11 preferably is raised from its support by yieldable foot members 14, three of which preferably are provided. The upper end of each foot member preferably is slotted to frictionally embrace an inwardly extending portion 15 of the respective walls whereby said members are securely held in place.

60

Two or more punch guide standards 16 are riveted or otherwise secured to suitable raised portions 17 on the base 11. If desired the portions 17 may be omitted or formed on the standards. Each standard 16 preferably is formed of sheet metal suitably bent, as best shown in Fig. 4, to provide a bottom wall 18 and parallel upwardly extending side walls or ears 19. A portion of one of said side walls is bent horizontally to rest upon the upper edge of the other side wall to provide a top wall 21. The bottom wall 18 and top wall 21 of each standard, are provided with registering openings 22 and 23, respectively, to receive and guide a punch 24. It is obvious that the two openings provide a rigid guide permitting only vertical movement of the punches.

Each punch 24 normally is held in its uppermost position by a suitable compression spring 25 mounted therearound between a collar 26 and the bottom wall 18 of the respective punch guide standard. An operating handle 27 preferably is provided with U-shaped arms 28, one of which is pivotally mounted by a pin 29 to each standard 16. Each arm 28 of the handle overlies one of the punches 24 and carries a pin 31 and roller 32 in substantial vertical alignment with the punch therebeneath, whereby upon movement of said handle downwardly the rollers engage and urge said punches downwardly, through the die openings 33 in the base 11, for perforating a sheet of paper inserted beneath the standards 16. The springs 25 return the punches and handle 27 to their normal raised positions which movement is limited by engagement of the rear end walls 34 of the arms with the edges of the walls 19 of the standards.

It is apparent from the foregoing that the punches 24 are freely moved vertically by operation of the handle 27 with a minimum amount of frictional resistance due to the rolling engagement between the rollers 32 and the punches. The pieces of paper punched through the die openings 33 drop onto the inclined end wall 35 of a receiving pan 36, which preferably is frictionally held to the underside of the base 11 by binding engagement with the side walls 12. A flange 37 preferably is formed on the forward end of said pan to facilitate its removal for emptying. An indicator 38 is provided to facilitate locating the sheets for proper spacing of perforations, which in this embodiment constitutes a depressable button for a purpose to become more apparent as the description proceeds.

A depression 39, slotted at each end as at 41, is provided in the top wall of the base 11 to afford a support for a gauge bar 42 which extends beneath the base through registering slots in the side walls thereof. The gauge bar 42 preferably has a gauging portion 43 at one end and a plurality 60 of spaced apart indicating markings 44 and apertures 45 on its face. At least one of the apertures 45 is adapted normally to be engaged by a detent projection 46 on the free end of a leaf spring 47, best shown in Fig. 5, which has its other end secured to the base 11. The indicator button 38, previously referred to, is mounted on spring 47 and extends through an opening in the base whereby upon depressing said indicator button, the detent projection 46 is moved out of engagement with hole 45 and the gauge bar may then be freely slid transversely of the base into another predetermined position, in which position another one of the holes 45 will be in position for engagement by the detent projections 46 upon release of the indicator button. Thus the gauge

bar, although being movable freely into various predetermined positions, is firmly held in any such position until released by the readily accessible indicator button 38.

In the forms of the perforating device illustrated in the remaining figures of the drawings, various parts thereof are identical with corresponding parts of the structure hereinbefore described and like numerals identify like parts.

In Fig. 6 the punch guide standards 16a (only one being shown) are each formed of a strip of material bent to provide top, bottom, and rear walls 21, 18 and 48, respectively. As shown, the rear wall 48 is inclined downwardly from the top wall 21 to the base 11 and extends along said base a sufficient distance to receive rivet 49. The end portion of the strap is bent upwardly and over upon itself to provide a bearing 51 to receive the pin 29 securing one arm 28 of the handle 27 thereto. Excessive upward movement of the handle 27 due to the action of punch springs 25 is restrained by engagement of the rear edge 34a of each arm with the top of base 11.

The structure shown in Fig. 7 is substantially like that illustrated in Fig. 6 except that the base 11 is upset at 17 to provide a rest for each standard 16b whereby its forward portion is spaced above the base 11.

In the perforating device illustrated in Fig. 8, each punch guide standard 16c (only one being shown) is formed of sheet metal bent to provide a cup-shaped portion 52 at its forward end and spaced apart rearwardly extending side walls or ears 19c. The bottom of the cup-shaped portion 52 has an axial flanged opening 22 to receive the lower end of punch 24. A collar 53, securely mounted near the upper end of the punch 24, co-operates with the inside face of the cup portion to maintain the punch in sliding vertical alignment.

The device illustrated in Fig. 9 also has punch guide standards each preferably formed of sheet metal bent to provide spaced apart side walls or ears 19d. A flanged guide sleeve 54 is welded or otherwise secured to the inside face of the bottom wall 18, in registration with the punch opening 22, around which the lower portion of expansion spring 25 is disposed.

In the modified form of perforating device illustrated in Figs. 10 and 11, each standard 16e is formed of a metal strap in a manner similar to the standards illustrated in Figs. 6 and 7 to provide top and bottom walls 21 and 18, respectively, and inclined rear wall 48. A portion 55 is struck from each rear wall 48 to provide bearings for links 56 which also are pivotally secured one to each arm 28 of handle 27. The laterally shiftable connection between handle 27 and standards 16e is necessary in this assembly because each punch 24 is secured by a pin 57 to the respective arm 28. The downwardly turned end portion 34 of each arm 28 engages the respective bearing portion 55 to limit upward movement of the handle.

In the perforating device illustrated in Figs. 12 and 13, each arm 28 of handle 27 is mounted in a standard 16f (only one shown) by pin 29 which operates in a slot 58 provided at the rear end of each of the side walls 19f of each standard to permit lateral shifting of the handle when depressed to carry the punch 24 vertically downwardly through the papers to be perforated. In this structure, however, a leaf spring 59, forked at 61, co-operates with a circumferential groove 62 in its associated punch normally to retain the punch 75

elevated. Opposed recesses or notches 83 on the edges of said springs adjacent their forward ends, embrace the end margins 84 of vertical slot 85 in the front wall 86 of each standard for guiding and maintaining the punch vertical.

Each arm 28 of the handle 27 of the perforating device shown in Fig. 14 has a downwardly and inwardly turned forked extension 87 on its pivotally mounted end, each of which embraces one punch 24 at the circumferential groove 88 to provide an operative connection therewith. The springs 25 bear against the respective extensions 87 to maintain the punches raised. Upward movement of the punches and handle are limited by engagement of the end 89 of each extension with the respective top walls 21g of standards 16g.

In Fig. 15 the side walls 19h of each standard (only one shown) are slotted at 71 to receive the ends of a horizontally disposed pin 72. The pin 72 carries a roller 73 which engages the top of the associated punch 24 for carrying the punch downwardly upon downward movement of the handle 27 which bears against the upper side of the pin 72 on each side of roller 73. The parts are maintained in this normal elevated position by compression spring 25.

In the perforating device illustrated in Figs. 16 and 17 the punch 24 has a pin 74 at its upper end upon which rollers 75 are freely mounted. The side walls 16 of the respective arms 28 of the handle 27 co-operate with the rollers 75 to carry the punch downwardly upon depression of the handle. The compression spring 25 returns the punch and handle to normal position upon release. To maintain the punch vertical at all times the pin 74 extends through vertical slots 77 in the spaced side walls 19j of standard 16j which preferably is formed of sheet material bent 40 and apertured on its rear end to receive the pin 29. A modified form of mounting for the foot 14j also is illustrated. The foot 14j (Fig. 17) has a portion 78 of reduced diameter which extends through an opening in a horizontally bent lip 79 formed by striking inwardly a portion of the side walls 12 of base 11.

The perforating device illustrated in Figs. 18 and 19 may embody any of the previously described types of standards 16 and punch mountings but, in this instance, incorporates a modified arrangement for gauging the sheet to be punched. As best shown in Fig. 18, the slideable gauge 42a, having a gauging portion 43 at its ends, is insertable beneath the base through slot 81 in one side wall 12, slots 41 at the ends of the depressed portion 39, and slot 82 in the opposed side flange 12. The gauge bar has a longitudinal slit 83 extending inwardly from the gauging portion end 43 terminating short of the opposed end of the gauge bar whereby said gauge bar normally is spread apart to frictionally bind against the edges of slots 81 to maintain said gauge bar in any predetermined position of adjustment. To release the gauge bar for shifting, its slit end is compressed. If desired, one or both longitudinal edges of the gauge bar may be serrated, as at 84, to increase the tendency of the bar to remain in an adjusted position. To retain the bar in position when it is almost entirely withdrawn from beneath the base, as when relatively large sheets of paper are to be perforated, the unslit end of said bar carries a detent or rivet 85 for frictional engagement with the edges of a slot 86 provided in the depressed portion 39 of base 11. The gauge bar is provided with a plurality of indicating

markings 44 which are selectively aligned with the offset edge 81 of one of the slots 81.

The gauge bar illustrated in Fig. 20 is substantially like that shown in Fig. 18 except that a yieldable rod 88 extends the entire length of the gauge bar 42b and is secured at 89 to one end thereof. In operation, the rod 88 is squeezed toward the gauge bar to disengage said bar from frictional engagement with the edge 81 of slot, which edge as well as the rods 88 may be corrugated to lock with edges of said slot.

The gauge bar 42c illustrated in Fig. 21 has gauging elements 48c formed on one end by folding portions of the gauge bar upwardly. These elements provide finger pieces to facilitate squeezing of the slit bar portions together. The opposed end of the bar is suitably slit, at 81, to provide normally spread apart portions 92 to frictionally engage the side walls of the depressed portion 39 of the base 11 when the bar is withdrawn to nearly its extreme limit.

In the perforating device illustrated in Fig. 22, the gauge bar 42d has a plurality of spaced notches 93 on one edge for co-operative engagement with edge of slot 81 in the side wall 12 of base 11. A suitable spring 94 normally retains the gauge bar in position for engagement by any one of the notches with the wall 12. The notch is disengaged upon moving the gauge bar transversely into the position shown in dotted lines and shifting it laterally.

In Fig. 23 the gauge bar 42e has a longitudinal slot 85 suitably notched at 86 for engagement with a detent projection 97 preferably formed in the depressed portion 39 of the base 11. The spring 94 normally retains one of the notches in engagement with detent 97 and upon transverse movement of the gauge bar into the dotted line position said bar may be shifted longitudinally to position another of the notches 96 for engagement with projection 97. In this embodiment the indicating markings 44 are coincident with notches 96.

The gauge bar 42f, shown in Fig. 24, preferably is made from yieldable material, such as spring steel, whereby it may be flexed into the dotted line position to disengage one of the series of holes 98 therein from a detent 99 in the top of the base 11 to facilitate shifting longitudinally.

In Figs. 25 and 26, the gauge bar 42g illustrated, preferably is formed of a strip of spring material folded upon itself at 101 to provide a gauging shoulder 43g and has its free ends slidably joined together by a suitable rivet 102. It is obvious that, when the gauge bar 42g is inserted through the various slots in the base 11, the normal tendency of the two thicknesses of spring material to spread apart maintains said gauge bar in any position of adjustment from which it may readily be shifted into any other desired position by momentarily squeezing the two thicknesses together.

In Fig. 27 the gauge bar 42h is held with one of its spaced holes 98 in engagement with a detent 99 in the base 11 by a suitable spring 103 which may be held in place on an inwardly turned lip 104 provided on the lower edge of one side wall 12 by pin 105.

It is to be understood that any of the various types of standards and novel means for mounting and operating the punches disclosed may be readily incorporated in any of the several perforating devices illustrated and that said perforating devices also may readily embody any one of the various forms of gauge bars disclosed herein. It is, therefore, not desired to limit the invention to the

precise details of any one illustration herein and it should be understood that the improved perforating devices may embody various other details without departing from the spirit of the invention or the scope of the appended claims.

I claim:

1. A perforating device including, a base, standards secured to said base, each having a guide opening, a plurality of punches one slideable in each guide opening, a transverse groove in each punch, a leaf spring in each standard slotted to engage the respective punch at the groove, said spring being guided in said standards to retain the punches vertical, an operating handle loosely journaled on said standards, and pins one connecting each punch to said handle.

2. A perforating device including, a base, standards secured to said base each having a guide opening and parallel side walls, a fulcrum pin mounted in each standard, a plurality of punches one slideable in each guide opening, a pin in each punch extending through vertical slots in each set of side walls, rollers on said pins, and an operating handle pivotally mounted on said fulcrum pin operatively engaging said rollers.

3. In a perforating device, the combination, with a base provided with parallel slots in its top and aligned slots in its side walls, said top being depressed between said parallel slots, of means for positioning sheets to be perforated including a gauge bar slideably in said slots beneath the top and over the depressed portion having indicating markings spaced along its length, and a shoulder on one edge of one of said parallel slots forming a pointer adapted to co-operate with said markings to assist determination of the relative position of said gauge bar with said device.

4. In a perforating device, the combination with a base having a depressed portion slotted at opposite sides, of a gauge bar slideable beneath said base and extending through said slots, a gauging portion on one end of said gauge bar, a slit in said bar extending longitudinally from said end normally holding portions of said bar spread apart, a plurality of spaced indicating markings on said bar, and serrations along one edge of the bar adapted to co-act with the base.

5. In a perforating device, the combination with a base provided with a depressed portion slotted at opposite sides and side walls having slots aligning with the depressed portion slots, of means for positioning sheets to be perforated including a gauge bar slideable in said slots and having a gauging portion at one end and indicating markings on its face, said gauge bar being slit longitudinally inwardly from the end having the gauging portion to permit compressing whereby said gauge bar may be released from its frictional retained position of adjustment.

6. In a perforating device, the combination with a base, of means for positioning sheets to be perforated including a bar slideable in said base, said bar having a gauging portion at one edge and indicating markings on its face, a plurality of notches on one edge to co-operate with the base for retaining the gauge bar in a selected position of adjustment relative to said base, and yieldable means on said bar to retain said notches and base interlocked.

7. In a perforating device, the combination with a base including a depressed portion slotted at each side, of a gauge bar slideable beneath said base and extending through said slots, said gauge bar having a slit extending longitudinally inwardly from one end normally holding the side

portions of said bar spread apart, and a finger piece on each portion of said bar at the slit end, said finger pieces forming gauging portions.

8. In a perforating device, the combination with a base, of means for positioning sheets to be perforated which include a gauge bar slideable in said base and having a gauging portion at one end and indicating markings on its face, and a yieldable element co-extensive with said gauge bar secured at one end to the opposite end of said gauge bar.

9. In a perforating device, the combination with a base including a depressed portion slotted at each side, of a gauge bar slideable beneath said base and extending through said slots, said gauge bar having slits extending inwardly from each end normally holding the side portions of said bar spread apart, and finger pieces at one end of said bar, said finger pieces forming gauging portions.

10. In a perforating device, the combination with a base, of means for positioning sheets to be perforated including a gauge bar slideable in said base, said bar having a gauging portion at one end and a plurality of notches on one edge to co-operate with the base for retaining the gauge bar in predetermined positions of adjustment relative to said base, and yieldable means on said bar to retain said notches and base in engagement.

11. In a perforating device, the combination with a base provided with a depressed portion slotted at opposite ends, of means for positioning sheets to be perforated including a gauge bar extending beneath said base and slideable in said slots, said gauge bar being made of spring material folded upon itself to normally spread apart whereby the base and depressed portion are frictionally engaged to retard free sliding of said gauge bar.

12. In a perforating device, the combination with a base, of means for positioning sheets to be perforated which include a gauge bar slideable in said base and having indicating markings on its face, and a movable portion joined at one end to one end of and constituting a part of said gauge bar, and a finger piece on the free end of each portion of said gauge bar, said finger pieces forming gauging portions.

13. In a perforating device, the combination with a base having a depressed portion slotted at opposite sides, of a gauge bar slideable beneath said base and extending through said slots, a gauging portion on one end of said gauge bar, and a stop at the other end.

14. In a perforating device, the combination with a base having a depressed portion slotted at opposite sides, of a gauge bar slideable beneath said base and extending through said slots, or gauging portion on one end of said gauge bar, said gauge bar being slit longitudinally inwardly from the end having the gauging portion, and a stop at the other end.

15. In a perforating device, the combination with a base having a depressed portion slotted at opposite sides, said depressed portion having a slotted aperture opening on one edge thereof, of a gauge bar slideable beneath said base and extending through said slots, a gauging portion on one end of said gauge bar, and a stop at the other end to co-act with said slotted aperture when the gauge bar is shifted longitudinally in one direction.
